UNITED STATES PATENT OFFICE

HERMAN E. WENDELL, OF ST. PETERSBURG, FLORIDA, ASSIGNOR TO STEEL-BOUND CONTAINER CORPORATION, A CORPORATION OF FLORIDA

CONNECTING PLATE

Application filed February 23, 1929. Serial No. 342,137.

My present invention is concerned with means for and methods of connecting, assembling, and holding various materials and forms permanently, or separable, and relates 5 more particularly to metal plates so cut and shaped as to provide means of this character which are of a novel, self-fastening type and dispense with nails or other fastening elements and which, in their generic aspect, may 10 take the form of polygonal metal plates of variable proportions having flat, angled, or reversely bent body portions.

Such connecting means are intended for use with and effectively connect in various positions and manners, materials such as usually require the use of nails, brads, etc., as exemplified by wood panels, veneers, molding, ply-boards, gypsum, wood and fibre boards, and sheet material similar to cork, 20 linoleum, rubber, etc. It is not feasible to use them where nails do not easily penetrate and they are therefore, not applicable to heavy structural timbers, framing elements, etc.

25 Connecting plates with differing forms and fastening elements have heretofore been proposed, but as constituted, they have lacked maximum efficiency through inadequate provision for attachment of the plates to their 30 supports so as to distribute supporting strain to resist displacement by thrust or pressure laterally from different angles.

Furthermore, the fastening means as heretofore proposed or provided, have been such 35 as to prevent complete contact of plate and support, the fastening tangs, therefore, not only securing inadequate anchorage, but holding the plate out of complete contact with the surface to which it is attached.

40 By my invention, plates of this character may be applied to the material of attachment to seat uniformly thereon or thereagainst with the supporting means resisting strain and displacement from a diversity of 45 angles and being of such a nature as to ensure penetration without splintering or splitting of the material penetrated, and with the material engaged thereby at such varying angles.

50 Accordingly, and generically stated, a fea-

ture of my invention consists in a polygonal metal plate, flat, angled, or reversely bent, having a plurality of pointed fastening tangs distributed about its edges, and bent out of the plane of the plate body on lines of diverse 55 angular relation into support entrant angles relatively to the adjacent portion of the plate body. These points or tangs are so located and grouped and bent as such angles relatively to the plate body that there is provided therefor, an anchorage characterized by anchor elements penetrating the support and positioned therein at diverse angles opposing lateral pull or strain on the plate from various angles. This diversity of angles not 60 only affords such support, but permits clustering or concentration of such diversely angled points without spreading or splitting of the grains of wood, for example, because of such diverse angles. In other words, in no 65 instance will the flat or broad face of a tang follow consecutively in line in any direction, and because of this, when attached to any material having a grain, the flat face of no 70 two consecutive tangs will follow a grain 75 line.

A further feature of the invention consists in the use of a plurality of diversely angled tangs with tangs of different angles having different lengths and extents of penetration, the lengths of those tangs of the same angle being similar or substantially so.

80 By this provision, the plate may be preliminarily and evenly disposed relatively to the support when a second or shorter series of tangs begin to penetrate as the plate is driven onto its support. The preliminary starting of the longer or first set of tangs into the support material ensures that the shorter or second set of tangs is driven in at the proper 85 angles, the diversity of angles tensioning the tangs in the support material and substantially increasing their holding power and resistance to displacement.

90 In the physical embodiment of the invention, I have provided, so far as the fastening tangs are concerned, various combinations and arrangements for varying conditions in 95 all of which diversity of support entrant angles occur.

I have further provided a novel method of forming these tangs which is both economical of material and labor, which method, in a related aspect, produces novel groupings of diversely angled pointed fasteners or tangs.

An outstanding feature of the method common to all groups of fastenings, is the utilization of the edges of the polygonal plates as a side or point, or both, of the tangs, by slitting the plates from the edges inwardly at determinate angles as will be fully explained hereinafter.

A particular example providing maximum efficiency is a corner group of fastenings formed by slitting the corner extremity at the junction of two sides of a polygonal plate inwardly from the edge extremity of the plate, and at determinate divergent angles providing a plurality of tangs bent on lines of diversely angular relation, and of at least, two divergent angles of support entry, and preferably, although not necessarily, two different lengths. Such corner groups of fastening tangs may be augmented, where the strain to which the plate connection is to be subjected justifies, by what I may term, side edge groups, the individual tangs of which are bent on lines extending inwardly from the plate edge at angles locating the broad faces of the tangs in the engaged material at angles opposing lateral dislocation.

The tangs or groups of tangs are bent either up or down from the face of the body of the plate. In many cases where a plate is to be used for connecting two overlapped or overlaid surfaces, two oppositely extending groups or tangs will be used. The wide field of use for such plates makes it impractical to illustrate in the accompanying drawings the manifold applications of the invention to practical use. It may be stated, however, that the angled forms of plate are used generally for corner bracing purposes, or for cooperation with another plate to form a detachable support. The reversely bent form of plate provides channels which may be cooperated with other forms of plates, for instance, an angled plate, to act as guide or support.

In the accompanying drawings forming part hereof, the invention is exemplified and phases of its application are illustrated. In the drawings:

Figure 1 is a plan view of a flat rectangular plate or body unit having its corners slit for the formation of corner groups of fastening tangs of one type, the lines and angle of bend of said tangs being indicated by dotted lines, with supplementing side groups of tangs indicated.

Figure 2 is a side elevation of said plate with the tangs bent upwardly therefrom at the appropriate angles of support entry.

Figure 3 is a view in edge elevation of a

group of the three basic forms of connecting plate to which the invention is applicable.

Figure 4 is a plan view of a flat rectangular plate having its corners slit for the formation of corner groups of fastening tangs of another type, the lines of bend for the tangs being indicated by dotted lines, and a different arrangement of supplementary side tangs being also dotted.

Figure 5 is an edge elevation of the plate with corner groups of tangs bent upwardly to the proper support entrant angle.

Figure 6 is a plan view of a plate showing a further different form of corner groups of tangs.

Figure 7 is an edge elevation thereof with the tangs bent up.

Figure 8 is a plan view of an angled connecting plate having one of the previously shown forms of corner tang groups with supplementing side tangs as shown in Figure 1.

Figure 9 is an edge elevation thereof with the tangs bent downwardly.

Figure 10 is a view showing the use of bent and angled connecting plates in cooperation as shelf hangers.

Figure 11 is a view of a connecting plate with opposed reversely directed tangs used to connect with concealed junction molding and furring strips.

Figure 12 is a view illustrating the use of coacting angled connecting plates for corner bracing.

Figure 13 is a plan view of connecting plate in the form of a strip with tangs formed thereon in accordance with the present invention.

Figure 14 is a plan view of overlapped rectangular connecting plates with reversely facing tangs for concealed connections.

Figure 15 is a view illustrating such plates applied to connect sheathing and wall board.

As I have previously stated, the connecting plates of the present invention may be of varied proportions, shapes and outlines, and I have designated the generic plates whether they be triangular or octangular as polygonal. For the purposes of illustration, a rectangular plate unit is shown, this plate unit having its body portion flat or in the same plane, or as indicated at A in Figure 3, being bent, the flat, angled, and bent forms illustrated in this figure of the drawings representing, generically, but not inclusively, the different type of plates available for use.

These plates, whatever their form, are made into connecting plates by slitting their edges inwardly at a determinate angle, and thereafter bending the triangular portions formed by the slits with the adjacent edge upwardly or downwardly from the plane of the plate body into support entrant angles, these tang portions being bent on lines in diverse angular relation. As shown, the line of bend

is predicated upon a line constituting a perpendicular to the line of slit.

The principal points at which the fastening tangs are provided are available corner extremities of the polygonal plates 1, supplemented where the size and character of the work requires, by supplementing tangs at intermediate points between the corners. A variety of corner tang groups embodying common underlying features is contemplated. One form which this corner group may take is formed by slitting the corner extremity inwardly at diverging angles as indicated at 2, 3, in Figure 1 of the drawings. These slits, in a preferred form determined by experimentation, form an approximate angle of 26° with the adjacent side edges of the plate. The slits 2 and 3 subdivide the corner of the plate into three triangular portions, the outer ones of which are triangles of similar angularity, with the central tang portion 4 having sides forming an angle of approximately 38°, or the difference between the form of the side tangs and a 90° angle where the corners of the plate are formed by sides joining at an angle of 90°. The line of bend of the outer corner tangs which are designated by the numerals 5 and 6 is a perpendicular to the line of slits 2 and 3 as suggested by the dotted lines 7 in Figure 1. These slits are preferably of the same length so that the tangs 5 and 6 will be of similar length. The intermediate tang portions 4, however, are bent on lines forming intermediate tangs shorter than the side tangs 5 and 6. These intermediate tangs 4, I prefer to bend out of the plane of the plate body 1 into a support entrant angles which are substantially perpendicular to the plane of the plate. The adjacent side tangs 5 and 6 are of a length which I prefer to bend out of the plane of the plate body into support entrant angles which extend beyond the perpendicular and incline toward a perpendicular extending from the center of the plane of the plate body. The lines of bend of the tangs, 4, 5 and 6 are, as will be clearly seen from an inspection of Figure 1 and also Figure 2, of diverse angular relation, no two consecutive lines being parallel. This diverse angularity at which the broad faces of the tangs will penetrate the engaged material not only is instrumental in preventing splitting of grained material, but offers resistance to displacement of the plate, when attached, along diversified lines of lateral strain. The different lengths of the intermediate tangs 4 and of the edge tangs 5 and 6 will permit an initial placement of the plate in the support material through the partial penetration of the side corner tangs 5 and 6. This will facilitate the driving of tangs 4 into the material at the proper angle by permitting the points of these tangs to be uniformly brought into contact with the surface of the material before being driven. Not only does this

diversity of the support entrant angle have this advantage, but the diversity of the angularity increases the hold of the plate through the material and retains it against strains tending to pull the plate away from the underlying face of the material as contrasted with lateral strains offset by the diversity of the angular relation of the broad faces of the imbedded tangs.

Where the plates are of sufficient size and the strain imparted is substantial, the support afforded by the corner groups of tangs may be supplemented by intermediate tangs or groups of tangs, one form of which is indicated by dot and dash lines in Figure 1 of the drawings and is designated by the numeral 8. These tangs are formed by slitting the edge of the plate at a common point, and in reverse directions from said point at angles with the adjacent side plates similar to those by means of which the tangs 5 and 6 are formed, the lines of bend being similarly based upon perpendiculars to the lines of slit.

The form of corner groups may be varied as previously indicated, the second form being shown in Figures 4 and 5, in which only the side corner tangs 5 and 6 are bent at the described angles, the intermediate portions 4 remaining in the plane of the body portion of the plate. Such a construction may be used where the support or connecting strain is less than is required by the first described form. As above suggested supplementing side tangs, shown by dot and dash lines in Figure 4, may also be used when desired, these tangs being designated by the numerals 9 in said figures, and representing continuations of the lines of side tangs 5 or 6, as the case may be. The lines of bend of the corner tangs 5 and 6 are shown in Figures 4 and 5, and likewise their diverse angularity, and where the supplementing tangs 9 are used, their lines of bend are also in diverse angular relation as suggested by the edge elevation of tangs 5 and 6.

The corner construction representing the third form embodies the combination of tangs of different lengths and angularity as in the first form and is shown in Figures 6 and 7 of the drawings in which single side tangs 6 are employed with adjacent triangular tang portions 10 bent on a line at an angle to the line of bend for the tang 6 and extending transversely of the corner to provide a shorter tang which, similarly to the tang 4 of the first form, is bent into a support entrant angle substantially perpendicular to the plane of the body of the plate 1, while the adjacent tangs 6 are bent beyond the perpendicular inclining toward the center of the plate. This construction provides corner groups of tangs having diversity of support entrant angles and angles of bend as suggested by the edge elevation of Figure 7. In this form of plate,

the support afforded by the corner groups of tangs may be supplemented by intermediate tangs 11 indicated by dot and dash lines in Figure 6, similarly to the first two forms of 5 corner tang groups described.

Obviously, the plates may have component 10 groups of tangs extending from opposite sides so that the plates may be used to interconnect two different members or parts as suggested by dotted lines in Figure 2, and as 15 shown in the mounting of the molding on a furring strip in Figure 11.

In the case of angled plate A and bent plate 20 B, Fig. 3 (which includes the angled form), 15 the corner extremities at the angle of bend are not available for the formation of tangs. In Figures 8 and 9 are shown respectively, a top plan view and an edge elevation of an 25 angled plate in which the available corner extremities are slit and bent downwardly as shown and described in Figures 1 and 2, and in which the lack of tangs at the opposite corner extremities is compensated for by supplemental side groups of tangs 8, similarly to 30 those described in connection with Figures 1 and 2. This same supplementation or compensation will hold true in the case of the bent plates B, being suggested by dotted lines 35 in Figure 9. The angled or bent plates may 40 employ, obviously, any of the different corner groups of tangs or supplemental side tangs, those shown being illustrative and not restrictive.

As illustrative of the use of angled and 45 bent plates, attention is called to Figure 10 of the drawings in which a bent plate 1b is imbedded by its tangs in a suitable support, its 50 reversely bent portion being lowermost and an angle plate 1a is secured to the underside 40 of a transverse member, say a shelf, to be supported, and angled portion of the plate 1a seating in the socket formed by the bent portion of the plate 1b, thereby affording a 55 detachable supporting connection.

50 The connecting plates when it is desired to use them for interconnecting two parts, such as the molding 12 and furring 13 of Figure 11, may have consecutive groups of corner tangs reversely bent as shown in Figure 11 and as suggested in Figure 2.

A similar function of interconnecting two parts, but with the parts out of contact may 55 be secured by overlapping rectangular connecting plates having plain intermediate portions and corner groups of tangs, so that the tangs project in opposite directions, one set of tangs being imbedded in a support such as the sheathing 14 of Figure 14, and the oppositely projecting tangs forming the underlying plate 1 being imbedded in the rear face 60 of wall board 15 when the latter is forced or driven thereon, thereby making a concealed support.

65 The angled connecting plates may be used in a variety of ways, such for example, as

bracing corners, drawer divisions, etc. In Figure 12 of the drawings, I have shown two angled plates 1a with their angled portions overlapped at an inside corner formed by horizontal and vertical wooden members 70 16-17. The same arrangement is likewise applicable to outside corners.

While the connection plate as heretofore described has been considered as a single plate, it may be logically developed and considered 75 in strip formation as a series of integrally connected plates. For example, in Figure 13, I show a strip fastener 18 having its end corners formed with tangs corresponding with the tangs 6 and 10 of Figures 6 and 7 (although either of the other forms of corner groups may be used), and with a series of 80 spaced groups of side tangs 6 which may be supplemented as suggested in dotted lines by slitting the edge at right angles as suggested at 19, and forming pairs of supplementing tangs 20 similar to the tangs 10. As suggested by the drawings, these tangs will be 85 in alignment at opposite sides of the strip 18, the dotted line 21 indicating an imaginary line marking the line of division between adjacent single aligned connecting plates integrally united in strip formation.

The foregoing description indicates partially the development of underlying features 90 of process and structure involved herein and which have been amplified so as to denote the scope of the inventive idea. The illustrations of the applications of the invention 95 are in the sense of illustration only, and not 100 of restriction.

Having described my invention, what I 105 claim and desire to secure by Letters Patent is:

1. A metallic fastener comprising a flat 110 polygonal metal plate having its marginal edges at a plurality of corner points provided with V-shaped cuts therein extending inwardly from apices at its corner edges, with the marginal portions bordering said cuts at 115 opposite sides of the apices of the V's bent inwardly on lines transverse to the side of the V's to form securing tangs with pointed penetrating ends extending outwardly from the plate with the faces of adjacent tangs 120 extending in planes in angular relation to each other and substantially at right angles to the plane of the flat plate body.

2. A metallic fastener comprising a flat 125 polygonal metal plate having its marginal edges at a plurality of corners provided with inwardly extending V-shaped cuts with the apices of the V's coinciding with the corners of the plate, the marginal portions bordering said cuts at opposite sides of the apices of the V's being bent inwardly on lines transverse to the sides of the V's to form securing tangs with pointed ends extending outwardly from the plate with their faces in planes in 130 angular relation to each other and substan-

tially at right angles to the plane of the flat plate, the intermediate marginal portion enclosed within the V being bent inwardly on a line transverse to the sides of the V to form 5 an intermediate pointed tang with its face extending in a plane in angular relation to the planes of the faces of the tangs at opposite sides thereof.

3. A metallic fastener comprising a polygonal flat metal plate having its marginal edges at a plurality of corner points provided with V-shaped cuts therein extending inwardly from apices at its corner edges, with 10 the marginal portions bordering said cuts at opposite sides of their apices bent inwardly on lines transverse to the sides of the V's to form securing tangs extending outwardly from the flat face of the plate substantially at right angles thereto with the 15 faces of adjacent tangs in planes in angular relation to each other, the marginal edges of said plate between said corner points and tangs being inwardly cut with marginal bordering portions bent inwardly to form 20 tangs intermediate the corner tangs with faces extending in planes in angular relation to those of said corner tangs.
